COMBINED CONTAINER CLOSURE AND OPENER THEREFOR

John E. Walsh, Beverly, Mass., assignor to United Shoe Machinery Corporation, Flemington, N.J., a corporation of New Jersey

Filed Feb. 7, 1961, Ser. No. 63,853

Term of patent 14 years

(Cl. D58—26)

FIG. 1 is a top plan view of a combined container closure and opener therefor embodying my new design;

FIG. 2 is a perspective view thereof;

FIG. 3 is a perspective view thereof at right angles to FIG. 2; and

FIG. 4 is a sectional view on enlarged scale taken on the line IV-IV of FIG. 1.

The dominant features of my design reside in a container closure with a diamond shaped break-out area and ringed pull-tab attached to the inner end of said break-out area as shown.

I claim:

The ornamental design for a combined container closure and opener therefor, substantially as shown and described.
